UNITED STATES PATENT OFFICE.

JOHN A. PILCHER, OF ROANOKE, VIRGINIA.

RAILWAY-CAR TRUCK.

Application filed August 13, 1921. Serial No. 491,989.

To all whom it may concern:

Be it known that I, JOHN A. PILCHER, a citizen of the United States, residing in the city of Roanoke, and in the county of Roanoke, State of Virginia, respectively, have invented certain new and useful Improvements in Railway-Car Trucks, of which the following is a specification.

This invention relates to side frames for railway car trucks and journal boxes therefor.

One object of the invention is to provide a truck side frame and a journal box therefor so constructed as to reduce the height of the journal box and to bring the side frame down low relative to the center of the axle.

Another object of the invention is to provide an improved form of construction of a journal box which obviates the necessity of employing a key or wedge for holding the journal bearing or parts in proper position in the box.

Other and further important objects of the invention will be apparent from the disclosures in the drawings and specification.

The invention (in a preferred form) is illustrated in the drawings and hereinafter more fully described.

Figure 1 is a broken side elevation of the preferred form of side frame and journal box. The journal box is shown one half as an end view from inside the side frame and one half as an end view from outside of the side frame.

Figure 2 is a side elevation of the journal box showing the end portion of the side frame in end elevation.

Figure 3 is a section taken approximately on the line 3—3, Figure 2.

Figure 4 is a section taken approximately on the line 4—4, Figure 1, illustrating the manner in which the bearing is placed in or removed from position.

Figure 5 is a broken side elevation view showing the manner in which the side frame may be raised relative to the journal box when the wheel, bearing or other parts have become worn.

Figure 6 is a section taken approximately on the line 6—6 of Figure 5.

Figure 7 is a broken inverted plan view of the journal bearing.

The improved box may be formed of either cast or pressed metal and comprises top, bottom and side walls 1, 2, 3 and 4, respectively, the top and bottom walls 1 and

2 being formed integral with or attached to the side walls 3 and 4. The bottom wall 2, which may be either formed flat or curved, is provided at its outer end with an upturned portion 5. A lid 6 of any suitable construction is pivotally connected to a lug 7 at the forward end of the top wall, and closes the forward end of the box. The inner end of the box is provided with an enlarged portion 8, having a guideway 9 for the dust guard (not shown in the drawings).

Disposed at either side of the journal box, there is a seat or bearing 10 for receiving the load from the side frame 11. Depending downward from the side frame 11, below the top of the journal box on either side thereof, are the arms or projections 12 and 13, which rest on the seats 10 of the journal box. These projections, or arms, 12 and 13, not only serve to transmit the load from the side frame to the journal box, but also serve to hold the journal box in a fixed position relative to the side frame, 80 longitudinally of the truck.

Both the seats 10 on the journal box and the bearings 14 on the side frame projections 12 and 13, are curved or semi-cylindrical in form. While the seats 10 on the box and the bearings 14 on the side frame are shown concave upward, they may be formed concave downward without interfering with the functioning of one on the other. Whenever the parts of the truck, wheels, bearings, etc., 90 become worn, permitting the side frame and car to move downward, they may be raised by applying one or more liners 15 between the seats 10 on the box and the bearings 14 on the side frame, as shown in Figures 5 and 6. The projections 12 and 13 of the side frame 11 are provided with lips or extensions 16, which serve to keep the liners 15 in position.

The side frame 11 is operatively attached 100 to the journal box by means of the bolt 17. The side frame is provided with one or more holes 18^a opposite which are vertical elongated openings 19^a in the journal box. Thus when one or more liners are applied 105 between the side frame and the box, the bolt 17 may be placed in the hole in the side frame, which is in line with the bottom of one of the vertical elongated openings in the box, thereby permitting the side frame 110 to be readily and easily raised relative to the box. The openings 19^a in the box are

elongated so that the box may be rotated in a transverse vertical plane relative to the side frame without removing the bolt 17.

Extending from the bottom side of the 5 bearings 10 on the box to the bottom thereof are the ribs or stiffeners 18, which help to transfer the load to the side walls 3 and 4. The load is transferred from the side walls 3 and 4 through the top wall 1 direct to the bearing 19, which is the American 10 Railway Association standard journal bearing. The inner side of the top wall 1 is formed to receive the upper angular surface of the bearing 19. The top wall 1 is 15 provided on the outer side with ribs or stiffeners 20, which reinforce the top of the box. On the inner side of the top wall 1 there are provided ribs 21, which reinforce the top wall 1 and also position the bearing 20 19 on top of the axle. The lugs 22 on the bearing 19 bear against the ribs 21 in the box and prevent the bearing from moving inwardly.

The bottom wall 2 of the journal box is 25 inclined upwardly towards the inner end of the box so that when the box is jacked up with a horizontal faced jack it will rotate about its inner end, taking the position shown in Figure 4. In this position the bearing 19 may be readily and easily removed or placed in position.

By having the bearings for the side frame 35 on the sides of the box rather than on top and not employing the ordinary key or wedge, the end of the side frame is brought down low relative to the center of the axle. Further, the load being transmitted to the box on the sides thereof rather than on the narrow top, stabilizes the box in the side 40 frame under the action of the brakes and forces other than the direct load.

Thus I have provided a truck side frame and journal box construction in which the bearing may be readily and easily removed or

placed in position and also one in which 45 the wear of the bearings, wheels, or other parts of the truck may be taken up. Furthermore, I have provided a construction in which the end of the frame is positioned low relative to the center of the axle. 50

There may be various modifications of the invention, and it is my intention to cover all such modifications which do not involve a departure from the spirit and scope of the following claims: 55

I claim:

1. In combination with a truck journal box, a side frame resting on arc-shaped seats disposed at the sides of the said journal box below the top thereof, liners interposed between said side frame and said arc-shaped seats on journal box for adjusting the height of said side frame relative to the journal box. 60

2. In combination with a truck journal box, a side frame resting on arc-shaped seats disposed at the sides of the said journal box below the top thereof, liners interposed between said side frame and said arc-shaped seats on journal box, projections on said 70 side frame for holding said liners in position.

3. In combination with a truck side frame, a journal box having vertical bearing surfaces at the sides thereof for holding it in a fixed position relative to said side frame, longitudinally of the truck and horizontal bearing surfaces at the sides and below the top thereof, whereby said box may rock on said side frame transversely of the truck, the said vertical bearing surfaces and the said horizontal bearing surfaces being so formed that said side frame may be lifted off said journal box in dismantling the truck. 80 85

In testimony whereof I affix my signature.

JOHN A. PILCHER.
